his Attorney

UNITED STATES PATENT OFFICE.

CHARLES C. MARTIN, OF WEST FRANKLIN, ASSIGNOR OF ONE-HALF TO
ROGER S. DIXON, OF MOUNT VERNON, INDIANA.

THILL-COUPING.

SPECIFICATION forming part of Letters Patent No. 510,078, dated December 5, 1893.

Application filed May 16, 1893. Serial No. 474,401. (No model.)

To all whom it may concern:

Be it known that I, CHARLES C. MARTIN, a citizen of the United States, residing at West Franklin, in the county of Posey and State 5 of Indiana, have invented certain new and useful Improvements in Thill-Couplings; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention relates to certain new and useful improvements in anti-rattling attachments for thill and pole couplings for vehicles, and it has for its object the provision of a simple, cheaply constructed and at the 20 same time efficient and durable device of this character, which may be quickly and easily adjusted at any time, so as to compensate for wear of the parts.

To these ends and to such others as the invention may pertain, the same consists in the peculiar construction, and in the novel combination, arrangement and adaptation of parts, all as more fully hereinafter described, shown 25 in the accompanying drawings, and then specifically defined in the appended claim.

30 The invention is clearly illustrated in the accompanying drawings, which, with the letters of reference marked thereon, form a part of this specification, and in which drawings—

35 Figure 1, is a longitudinal, vertical section through my device, the same being shown in connection with the thill iron of a vehicle. Fig. 2, is a perspective view showing the several parts as separated, but in their relative 40 positions.

Reference now being had to the details of the drawings by letter, A designates the arm or "clip" to which the thill iron B is attached in the usual manner, by a transverse bolt C which is passed through the eyes or openings D, D at the outer ends of the arms E, E of the arm A, and through the eye F of the thill-iron G.

H is a metallic plate having its side edges recessed or cut away, as shown at H', the 50 width of said recesses corresponding with the thickness of the arm A. This cutting away of the side edges of the plate H forms at the corners of the plate short lugs or extensions H², H², which lugs, when the plate is in position, as shown in Fig. 1 of the drawings overlap the upper and lower edges of the arms E of the arm A, and serve to retain the plate in position and preventing its being laterally 55 displaced, while at the same time they do not 60 interfere with the movement of the plate in the direction of the length of the arms E.

I is a plate which in thickness and in general form is similar to the plate H, the essential features of difference between the plates being that the plate I is provided upon its outer face with a curved or concave surface I' to engage the curved end of the thill-iron, while the rear face of the said plate is provided with 70 an integral screw-threaded shank or extension I².

J is a nut (preferably circular, as shown), which nut is screwed upon the shank I² of the plate I, the rear end of the nut being cut 75 away, or of lessened diameter, so as to engage the shoulder K in the face of the plate H, against which it bears.

The outer face of the nut J is provided with a series of openings j, j, to receive the 80 end of a tool which is employed in turning the nut, as will be readily understood. It will be seen that by this construction a very simple device, of few parts is provided, which, without the aid of springs of any kind will 85 serve at all times to hold the thill coupling against possible rattling, the wear of the parts being readily adjusted by simply turning the nut J.

Having thus described my invention, what 90 I claim to be new, and desire to secure by Letters Patent, is—

In combination, the thill-iron, the receiving clip, the bolt connecting said clip and iron, the plate H fitted between the arms of the 95 clip and recessed at its sides and having cir-

cular recess in its outer face the plate I having one of its faces concaved as described to engage the curved end of the thill-iron, the screw threaded shank at the rear of the said plate, and a nut upon said shank to adjust the position of the plate and seated at one end in the recess of the plate H, substantially as described and for the purpose specified.

In testimony whereof I affix my signature in presence of two witnesses.

CHARLES C. MARTIN

Witnesses:

SAMUEL G. DIXON,
GENERAL G. DIXON.
